TELEPHONE HAND SET

Isaac Heller, Maplewood, N. J., assignor to Remco Industries, Inc., Newark, N. J., a corporation of New Jersey

Application February 14, 1955, Serial No. 34,503

Term of patent 14 years

(Cl. D26—14)

To all whom it may concern:

Be it known that I, Isaac Heller, a citizen of the United States of America and a resident of Maplewood, county of Essex and State of New Jersey, have invented a new, original, and ornamental Design for a Telephone Hand Set, of which the following is a specification, reference being had to the accompanying drawing, forming a part thereof.

I claim:

The ornamental design for a telephone hand set, as shown.
